UNITED STATES PATENT OFFICE

99,519

DESIGN FOR AN INITIAL OR OTHER CHARACTER BEARING HOLDER

Edwin S. Mix, Rochester, N. Y., assignor to
Hickok Manufacturing Company, Rochester,
N. Y., a corporation of New York

Application February 1, 1936, Serial No. 60,951

Term of patent 7 years

To all whom it may concern:

Be it known that I, Edwin S. Mix, a citizen of the United States, residing at Rochester, in the county of Monroe and State of New York, have invented a new, original, and ornamental Design for an Initial or Other Character Bearing Holder, of which the following is a specification, reference being had to the accompanying drawing, forming part thereof.

The figure is a perspective view of the initial or other character bearing holder showing my de-

sign, the dominant feature thereof residing in the arrangement of the character bearing panels between the spaced bars; the particular initials shown in dotted lines being merely illustrative.

The back of the holder shown is substantially plain, that is, plain to the extent of being devoid of ornamental characteristics.

I claim:

The ornamental design for an initial or other character bearing holder, as shown and described.

EDWIN S. MIX.
